CLIP FOR GUARD BOARDS OF SCAFFOLDS AND THE LIKE

Filed June 18, 1929

Inventor;
Arnold Clarence Marshall,
By his Atty, *Marshall D. Penney*

UNITED STATES PATENT OFFICE

ARNOLD CLARENCE MARSHALL, OF LONDON, ENGLAND, ASSIGNOR TO THE STEEL SCAFFOLDING COMPANY LIMITED, OF LONDON, ENGLAND, A CORPORATION OF GREAT BRITAIN

CLIP FOR GUARD-BOARDS OF SCAFFOLDS AND THE LIKE

Application filed June 18, 1929, Serial No. 371,930, and in Great Britain July 24, 1928.

This invention relates to a clip for guard-boards of scaffolds and the like.

According to present practice the guard-board or boards at the edge of the platform 5 of a scaffold is or are secured by lashing or nailing them to the scaffold poles.

The present invention has for its object to provide a simple form of device whereby the lashing or nailing is avoided and, further, to 10 enable a number of boards or planks to be secured edge to edge, not only for the purpose specified but for constructional purposes generally.

A clip according to this invention comprises 15 a substantially U-shaped body, preferably formed of flat metal, one limb of which at its outer extremity is provided upon its upper side with an upwardly extending lug or projection and upon its under side with a down- 20 wardly projecting lug or the like. The projections, where the device is formed of wrought or malleable metal, are conveniently formed by incising the limb for a suitable 25 distance from its outer end longitudinally and bending the parts in the desired directions, the bent portions lying in the same plane.

The second limb is provided at its outer 30 end with a lug or projection which projects downwardly. At a convenient distance from the outer end of the limb a second projection is formed also projecting downwardly. The limb just referred to is preferably incised longitudinally and centrally of its length, the outer half being turned or bent downwards 35 to form the inner projection.

In use the device is placed upon the scaffold pole, said pole lying snugly within the crutch thereof, the limbs projecting forwardly of the pole, the distance between the outer surface of the inner projection upon the second 40 limb and the plane parallel thereto in which lies the rearmost edge of the said crutch being equal to the diameter of the pole. The arrangement is such that the guard-board is 45 retained against displacement on one side by the downwardly extending projections at the outer ends of the limbs of the device, and on the other side by means of the pole and the inner downward projection of the second 50 limb. In order to prevent accidental dis-

placement of the device a perforation may be provided in one of the limbs through which a nail may be driven into the edge of the board, the outer end of the nail being turned or bent over.

The purpose of the upwardly extending lug previously referred to is to engage the lower edge of a further guard-board or the like should it be desired to place this above the first mentioned guard-board, for as will be 60 readily understood the height of the guard may be increased to any desired extent by employing a number of clips and boards.

A clip according to the present invention may, if desired, be employed for constructional purposes, and permits of the ready and rapid erection of temporary or other buildings, the planks or boards comprising the walls of which may be readily assembled and held to posts or uprights. Again, clips according to this invention may be used for securing floor or other boards or planks to horizontal supports, such for example as the put-logs of scaffolding.

Where used for constructional purposes to form a hollow wall one clip may be applied to a vertical member to engage a board upon one side thereof and a second clip to engage a board upon the other side, the boards thus being retained in spaced relationship, the distance between them being equal to the diameter or thickness of the vertical member.

Obviously as applied to a pole of other than circular cross sectional outline the outline of the crutch portion of the clip would be suitably modified.

In order that the invention may be the better understood the accompanying drawings are appended showing one form of the invention in which:

Fig. 1 is a perspective view of the clip.

Fig. 2 is a side view showing the clip applied to scaffolding.

Fig. 3 is a front view of the clip in use.

Fig. 4 is a view showing a further application of the clip.

Referring to the accompanying drawings, *a* indicates a substantially U-shaped body formed of flat metal and designed to partially surround a scaffold pole *b*.

c and *d* indicate the limbs of the body *a*, the limb *c* being provided at its outer extremity and upon one side with a lug *e* extending therefrom at a right angle and upon its other side with a similar lug *f* of a somewhat greater length than the lug *e*.

The limb *d* is provided at its outer end with a lug *g* projecting therefrom at a right angle and in the same direction as the lug *f*, whilst at a suitable distance from the outer end of the said limb a lug *h* is formed extending in the same direction as the lug *g*, the said limb *d* being preferably incised longitudinally and centrally of its length, the outer half being turned or bent to form the lug *h*. The lug *h* is so disposed that its outer surface is situated within a plane tangential to the circumference of the pole *b*.

i indicates a guard-board which is retained against displacement on one side by the projections *f* and *g* and on the other side by means of the pole and the projection *h*. The purpose of the lug *e* is to engage the lower edge of a further guard-board or the like should it be desired to place this above the board *i*, for as previously stated, by employing a number of clips the height of the guard may be increased to any desired extent.

j indicates floor boards or the like secured by means of the clip to the horizontal member or put-logs of the scaffolding, the said boards being disposed at, or substantially at, right angles to said put-logs, with the clips partially surrounding the put-logs, and with the projections *e*, *f*, and *g*, engaging the upper surfaces of the boards to thus prevent their vertical displacement.

k (Fig. 1) indicates a perforation provided in the limb *c*, through which a nail may be driven into a board held by the clip for the purpose of preventing the accidental displacement of the said clip.

Fig. 4 shows the application of the clip to secure boards upon both sides of a vertical member or support.

As will be readily understood, for the purpose of cheapening the cost of manufacture of the clip, the projection *f* may, if not required, be dispensed with.

50 Claims:

1. A device for the purpose specified comprising two parallel members disposed in spaced relationship, a connection between one end of said members, downwardly extending projections at the end of one member arranged in spaced relationship one to the other, a downwardly extending projection at the end of the other member, and an upwardly extending projection upon said member.

2. A device for the purpose specified comprising two parallel members disposed in one plane and in spaced relationship, a connection between one end of said members, downwardly extending projections at the end of one

member disposed in spaced relationship one to the other and lying in parallel planes, a downwardly extending projection at the end of the other member, and an upwardly extending projection upon said other member, said projections lying in the same plane.

3. A device for the purpose specified comprising a metal body having parallel members lying in the same plane, a portion connecting said members at one end thereof, an extension at the end of each member disposed at a right angle to the plane thereof, said extensions lying both in the same plane, a second extension upon the end of a member also disposed at a right angle to the body of the device and lying in a plane parallel to but behind the plane of the first extension, and a second extension upon the other member also disposed at a right angle to the plane of the body of the device, but projecting in the opposite direction to said first projection upon said member and lying in the same plane.

4. A device for the purpose specified comprising a U-shaped metal body, one limb of which is provided with two downwardly directed projections parallel to each other but lying in planes one behind the other, a downwardly directed projection upon the other limb parallel to the outer projection of the first limb and lying in the same plane, and a second upwardly directed projection upon said limb lying in the same plane as said first projection upon said limb.

5. A device for the purpose described comprising two parallel members disposed in spaced relationship, an integral connection between one end of said members, the other end of one of said members having an upwardly turned projection and a downwardly turned projection, and the other end of the other of said members having one or a plurality of downwardly turned projections.

6. A device for holding together guard-boards of scaffolds and the like comprising two parallel members disposed in spaced relationship, a connection integral with said members between one end of said members, a plurality of projections upon the end of one member respectively engaging the outer and inner faces of a guard-board and disposed at a right angle to the plane of said members, and a projection at the end of the other member designed to engage the outer face of a guard-board.

7. A device for the purpose described comprising two parallel members disposed in spaced relationship, a connection integral with said members between one end of said members, a plurality of projections upon the end of one member respectively engaging the outer and inner faces of a guard-board and disposed at a right angle to the plane of said members, a projection at the end of the other member designed to engage the outer face of a guard-board.

gaged by the first pair of projections and the outer face of a second guard-board disposed edge to edge with respect to said first guard-board.

5 In testimony whereof I have hereunto set my hand.

ARNOLD CLARENCE MARSHALL.
